DESIGN FOR AN AIRCRAFT CARRIER

Orlo A. Bartholomew, Northfield, N. J.

Application September 29, 1942, Serial No. 108,439

Term of patent 7 years

To all whom it may concern:

Be it known that I, Orlo A. Bartholomew, a citizen of the United States, residing at Northfield, in the county of Atlantic and State of New Jersey, have invented a new, original, and ornamental Design for Aircraft Carriers, of which the following is a specification, reference being had to the accompanying drawing, forming part thereof.

In the drawing,

Fig. 1 is a top plan view of an aircraft carrier showing my new design;

Fig. 2 is a side elevational view thereof;

Fig. 3 is a rear elevational view thereof the stack and observation turret portions having been omitted for convenience of illustration and

Fig. 4 is a front elevational view thereof the stack and observation turret portions having been omitted for convenience of illustration.

I claim:

The ornamental design for an aircraft carrier, as shown.

ORLO A. BARTHOLOMEW.
